TEXTILE STRAPPING MACHINE

Donald E. Black, Chicago, Willard E. Collins, Clarendon Hills, James N. Wegnum, Chicago, and John Ekern Ott, Hinsdale, Ill., assignors to Acme Steel Company, Chicago, Ill., a corporation of Illinois

Application November 15, 1952, Serial No. 320,794

7 Claims. (Cl. 100—25)

This invention relates to improvements in textile strapping machines and its purpose is to provide an improved machine for compressing bundles or packages of textiles or other compressible materials and then encircling them with metal binding straps which are drawn taut to hold the bundles, packages, boxes, containers or other shipping units in their compressed condition to facilitate the handling thereof during shipment or subsequent use.

In the field of packaging, and particularly in the packaging of textiles, it is common practice to enclose the textile materials in fiberboard containers of the telescoping type and to close the containers and compress their contents preliminary to applying binding straps thereto. The closing of the container and the compression of its contents has usually been effected by the act of drawing the straps taut around the container preliminary to joining the ends of the straps, with the result that the tension of the different straps has not been uniform and the straps have often cut into the edges of the containers in the process of being drawn taut. These operations have required the attention of a plurality of workmen in connection with the binding of each package or bundle and the operation has been necessarily time-consuming and expensive.

Further, in the operation of applying binding straps to bales, bundles or packages of various types, by the use of a press, it has been the practice to employ workmen on opposite sides of the bundle or package to thread the straps through the grooves in the pressure platens of the press located above and below the bundle or package to cause them to encircle the object to be bound, and this has been followed by the use of manually operated tools for joining the ends of each strap. This practice has also been costly because of the labor requirements and because the rate of production for a single press was very low.

The principal object of the present invention is to provide an improved strapping machine in which the operations of extending the binder around the package or bundle and then drawing it taut are performed automatically under the control of a single operator who then causes the binder to be cut from the supply and its ends to be secured together, thus requiring a minimum of manual labor. A further object of the invention is to provide a strapping machine comprising means for compressing the bundle or package and maintaining it in that compressed condition while applying one or a plurality of binding straps around it and creating a substantially uniform condition of tension in each strap. A further object is to provide a baling machine comprising means for causing a plurality of flexible binders to be automatically drawn from supply coils and simultaneously extended around a bale or bundle preliminary to the operations of drawing the binders taut, cutting them from the supply coils and then securing the ends of each bundle encircling binder together. Another object of the invention is to provide power driven strap feeding means for draw-

2

ing a strap from a supply, extending it automatically around a bundle and then, after its end has been gripped, reversing its action to draw the strap taut around the bundle. Still another object of the invention is to provide a strapping machine comprising means for automatically extending a strap around a bundle, means for drawing the strap taut around the bundle, means for cutting it off from the source of supply and means for joining the ends of the taut strap, preferably in combination with means for causing all of these operations to be effected by power driven means under the convenient control of a single operator. A further object of the invention is to provide improved means for guiding the steel strap in its travel around the bundle, including magnetic means for releasably holding the strap during its travel. Other objects relate to various features of construction and arrangement which will appear more fully hereinafter.

The nature of the invention will be understood from the following specification taken with the accompanying drawings in which one embodiment of the invention is illustrated. In the drawings,

Figure 1 shows a front elevation of a machine embodying the invention;

Fig. 2 shows a side elevation of the machine illustrated in Fig. 1;

Fig. 16 shows a sectional view taken on the line 16—16 of Fig. 7;

Fig. 17 shows a horizontal section taken on the line 17—17 of Fig. 13;

Fig. 18 shows a partial vertical section taken on the line 18—18 of Fig. 17, illustrating the sealing head of the sealing device in its extreme elevated position in which it is adapted to receive a seal from the lower end of the magazine in which the seals are stored for use;

Fig. 19 shows an enlarged horizontal section through the sealing jaws, taken on the line 19—19 of Fig. 18;

Fig. 20 shows a vertical section on the line 20—20 of Fig. 18, illustrating the sealing jaws and the movable cutting blade in their elevated positions;

Fig. 21 shows a partial enlarged front elevation of the apparatus illustrated in Fig. 13 with parts thereof broken away, illustrating by full lines the position of the sealing lever and associated parts after the sealing head has been lowered and before the jaws have been actuated to form an interlocking joint, and illustrating by dotted lines the relative position of the sealing lever and associated parts after this lever has been actuated to operate the sealing jaws for the purpose of deforming the strap ends and the seal;

Fig. 22 shows a detailed section taken on the line 22—22 of Fig. 21;

Fig. 23 shows a detailed section taken on the line 23—23 of Fig. 21;

Fig. 24 shows a perspective view of the toothed pin on which the sealing lever is mounted;

Fig. 25 is a perspective view of the bearing member engaged by one end of the pin illustrated in Fig. 24;

Fig. 26 is a perspective view of the cover plate which is mounted on the outer end of the bearing member shown in Fig. 25;

Fig. 27 is a vertical section showing a side elevation of the latch mechanism for controlling the seal feed;

Fig. 28 is a perspective view of the latch member embodied in the mechanism shown in Fig. 27;

Fig. 29 is a perspective view of the gripping dog which holds the free end of the strap in the sealing device after it has passed around the bale or bundle together with the operating connections thereto for controlling its actuation during the strapping cycle;

Fig. 30 is a diagrammatic view showing the various parts of the fluid pressure operated system by which various operations of the baling machine are effected; and

Fig. 31 shows a schematic diagram of the electric circuit by which the fluid pressure operated devices are controlled.

As illustrated in the drawings, the invention is embodied in a baling machine comprising a horizontal base 40 adapted to rest upon a floor or other support and having secured thereto a vertically extending frame 41 comprising two side frame members 42 and a connecting top cross frame member 43. The vertical frame members 41 are of channel form having their flanges directed away from each other and they are arranged to support a vertically movable pressure platen 45 which is adapted to be lowered for the purpose of compressing a bale or bundle 46 which rests upon the stationary platen formed by the base 40. The base 40 comprises transverse channel-shaped frame members 40a which are connected to upright longitudinally extending frame members 40b and the frame structure thus formed has mounted thereon a plurality or series of cylindrical rollers 47 having their pinions journaled in brackets 48 which are carried by the frame members so that the rollers provide the immediate support for the bale or bundle 46 which may be rolled on to the base from a suitable conveyor at one side of the machine and discharged therefrom on to another conveyor at the other

side of the machine after it has been compressed and strapped.

The movable pressure platen 45 comprises a pair of side plates 50 which extend on the inner sides of the upright frame members 42, as illustrated in Fig. 1, and these side plates are connected by a channel-shaped transverse frame member 51, located adjacent to the upright frame members 42, and also by a transverse channel-shaped frame member 52 located at the forward end of the pressure platen, as well as by a transverse frame member 53 which connects the upper ends of the side plates adjacent the forward edges of the upright frame members 42. Each of the side plates is provided with two pairs of rollers 54 mounted on pins 55 which extend laterally therefrom, as shown in Figs. 1 and 2, and these rollers are adapted to coact with the front and rear sides of the upright frame members 42 which serve as track members for the pressure platen 45 during its vertical movement.

In order to counterbalance the weight of the pressure platen 45 and the parts carried thereby, the transverse frame member 53 thereof is connected near its ends to two flexible cables 56 which extend upwardly and over pulleys 57 which are journaled in brackets mounted in slots formed in the upper ends of the frame members 42. After the cables 56 have been extended over these pulleys 57 they are directed downwardly and secured to counterweights 58 which are mounted to move vertically in the sheet metal housings 59 of U-shaped cross section which are secured to the outer sides of the members 42. Through the provision of these counterweights, a minimum of effort is required to effect the vertical movement of the pressure platen 45 and the parts of the machine which are mounted thereon.

The pressure platen is moved vertically by fluid pressure operated means connected to two U-shaped brackets 66 which have their arms secured in the transverse member 53 of this pressure platen. These brackets are secured to piston rods 61 which extend downwardly into the cylinders 62 which are pivoted at the points 63 on the base 40. Pistons are secured to the piston rods 61 within the cylinders 62 and, when compressed air or the like is admitted to the lower ends of these cylinders, the pistons are actuated to move the pressure platen 45 upwardly, while the admission of compressed air or the like to the upper ends of the cylinders 62 causes a downward movement of the pressure platen for the purpose of compressing the bale or bundle 46.

When the bundle or package 46 has been closed or compressed to the desired extent, one or more steel binding straps 65 are passed around the bundle by power operated means carried by the pressure platen 45. In the embodiment illustrated, means are provided for causing the compressed bundle to be bound by three flexible steel straps which are fed around the bundle by three separate but simultaneously operated feeding devices. These feeding devices 60 are mounted on the forward end of the pressure platen 45 and the metal straps 65 are drawn thereto over pulleys 67 which are mounted in slots located in the upper ends of the vertical portions 70a of guide channels 70, which serve as tracks for the moving straps after they have passed the feeding devices 60. The metal straps are drawn from supply coils or the like, not illustrated, and travel in the direction of the arrows 71 on the inner sides of pulleys 72 which are carried by brackets 73 mounted on intermediate parts of the upright portions 70a of the guide member 70. The straps then pass upwardly and over the pulleys 67 and thence downwardly in a forwardly inclined direction to the feeding devices 60. From the feeding devices 60 the straps extend along the underside of the pressure platen 45 through strap sealing devices 75 and they then enter the guide channels 70, being directed by the lower curved portion 70b of these guide channels to the forward

upright portions 70c thereof where the free ends of the straps are projected to be seized by the operator and placed in operating engagement with gripping members of the sealing devices 75 in readiness to be drawn taut around the bales or bundles.

Each strap 65 is discharged from the upright portion 70c of its guide channel in proximity to a housing 77 mounted upon the upturned end of a conduit 78 through which electric connections are made with a plurality of push buttons 78 adapted to be actuated by the operator for the purpose of controlling the electric circuit by which the various fluid pressure operations of the machine are regulated and controlled. As the strap 65 is discharged from a guide channel 70c it passes through a housing 80, shown particularly in Figs. 3 and 4, which contains a pair of upright bars 81 forming a channel 82 through which the metal strip passes. These bars 81 are provided adjacent their lower ends with apertures to receive a pair of grooved rollers 83 and 84, one of which has its bearings in a stationary bracket 85 secured to one of the bars while the other roller 84 has its trunnions journaled in a lever 86 which is pivoted at 87 on arms 88 extending from the other bar 81. A coil spring 89 mounted on the pin 87 is arranged to actuate the lever 86 to move the roller 84 toward the roller 83 so that the two rollers will engage the opposite edges of the strap 65 passing through the housing. At its other end the lever 86 is provided with a pin 89a having a screw threaded engagement therewith and adapted to contact the actuating pin 90a of a switch 90 which is connected in the electric circuit hereinafter described for controlling the actuation of the associated feeding device 69 by which a strap is fed to this particular housing 80. When the strap 65 is projected upwardly through the housing 80 it separates the rollers 83 and 84 with the result that the switch 90 is actuated to stop the associated feeding device 69 and the parts are so arranged that there is some delay in the stopping of the feeding device so that, when the stoppage is finally effected, the end portions 65a of the strap will project above the housing 80 and the switch housing 77 so that it may be gripped by the operator for bending it over into engagement with a gripping dog mounted upon the associated sealing device 75, as hereinafter more fully described.

The arrangement for guiding the strap, feeding it, arresting the feeding operation, drawing the strap taut around the bundle, cutting it off from the source of supply and forming an interlocking joint between its overlapping ends are the same for each of the straps 65 and a description of one of these units will suffice for all of them. After passing over a roll 67 at the upper end of the frame 41, each strap passes downwardly to a feeding device 69 which is shown particularly in Figs. 1, 3, 5 and 6 where it is shown as comprising a supporting frame 91 mounted upon a supporting plate 92 which extends between the side plates 50 of the pressure platen 45. The upright portion of this frame 91 has mounted therein a horizontal bolt 93 which serves as a shaft for supporting an idler feed wheel 95 which is mounted to rotate about the bolt 93 through an intermediate ball bearing unit 96 which seats against the head of the bolt and against a washer 97 mounted between it and the frame 91. The outer ring of the ball bearing unit 96 is held in place by a retaining ring 98. The peripheral surface 95a of the feed wheel 95 passes in close proximity to a driving feed wheel 100 which is secured upon the shaft 101 of a driving motor 102, which is preferably a motor of the rotary impeller type actuated by air under pressure. This motor is secured by studs 103 to a supporting member 104 which is pivoted by a pin 105 on the frame 91. The outer end of the shaft 101 is journaled in a ball bearing unit 106 mounted in the depending portion 104a of the supporting member and this arrangement allows the driven feed wheel 100 to rest by gravity upon the strap 65 which passes between it and the idler feed wheel 95.

In order to regulate the pressure with which the feed wheels 95 and 100 engage the strap, the supporting member 104 is arranged to be actuated about its pivot by a coil spring 107 mounted upon a stud 108 which threadedly engages the frame 91 and extends upwardly therefrom within a cylindrical recess 104b which is formed in the supporting member. The lower end of the spring engages the bottom of this recess and the upper end engages a washer 109 secured against the spring by an adjustable nut 110 which may be regulated to control the compression of the spring 107 and the resulting pressure with which the feed wheel 100 engages the upper side of the strap.

The strap 65 passes to the feed wheels 95 and 100 through a guide member 111 which is secured to the supporting member 104 by studs 112 and, as the strap moves downwardly from the feed wheel 100 it engages another guide member 113 which is secured to the frame 91 by studs 114. This guide member 113 conforms generally to the peripheral surface 95a of the feed wheel 95 but diverges slightly therefrom and it terminates in a straight portion 113a, located at the right of the feed wheel 95 as viewed in Figs. 3 and 5, from which point the strap 65 passes to the guide members of the adjacent sealing device 75.

After passing through the guides of the sealing device 75, the strap 65 passes beneath a series of magnetic rollers 115 which have their trunnions journaled in brackets 116 secured to the frame structure of the pressure platen 45. These rollers are adapted to hold the strap above the bale or bundle 46 by magnetic attraction and after passing in contact with these rollers, the strap 65 engages another series of similar magnetic rollers 117 journaled in brackets 118 which are carried by a curved guide member 119 extending rearwardly and downwardly from the lower part of the cross frame member 51 of the pressure platen. The magnetic rollers 117 extend slightly below the guide members 119 so that they direct the strap into engagement with the upper parts of the guide channels 70 which have previously been referred to. The upright portion 70a of each guide channel is provided with another series of magnetic rollers 120 which are located in apertures formed in the bottom wall of the guide channel and which have their trunnions journaled in brackets 121 carried by this portion of the guide channel. The rollers 120 extend slightly beyond the inner surface of the upright portion of the guide channel and are adapted to attract the metal strap and hold it as it passes downwardly to the curved bottom portion 70b of the guide channel by which it is guided under the bale or bundle 46 and then deflected upwardly into the upright portion 70c of the guide channel. The magnetic rollers 120 are spaced apart vertically along the upright portion 70a of the guide channel so that one or more of them will be engaged by the strap with the pressure platen 45 in any position which it may occupy. The lowermost roll 120 is located in proximity to the place where the strap will be discharged by the magnetic rollers 117 when the pressure platen 45 is in its lowermost position.

The magnetic rollers 115, 117 and 120 and their mountings are substantially alike and a description of the rollers 120 will suffice for all of them. As shown in Fig. 11, each roller 120 is mounted upon a shaft 122 of non-metallic material which is journaled in two brackets 121 carried by the side walls of the upright portion 70a of one of the guide channels 70. Each roller 120 comprises an intermediate cylindrical member 120a which is a permanent magnet, being formed of a highly magnetic alloy such as that known to the trade as "Alnico 5," and this member contacts on its ends with two other similar members 120b which are of larger diameter than the intermediate part 120a and are provided at their outer edges with inwardly directed annular projections 120c which are spaced apart to leave an air gap 124 between them. With this arrangement, the magnetic flux set up by the permanent

magnet 120a passes through the roller portions 120b which are formed of magnetizable material, and thence across the air gap 124 or through the steel strap when the steel strap is in contact therewith. In this way the steel strap is temporarily attracted and held by the roller 120 while it is in contact therewith during its travel. In order to prevent the steel strap from bending around the roller and following its curvature instead of continuing in a straight line, a spacer 125 of bronze, aluminum or other nonmagnetizable material is mounted between each pair of rollers 120b in alignment with the air gap 124 so that it will engage the metal strap above and below the roller 120 to maintain the desired direction of travel of the strap.

Each strap sealing device 75 has the form which is illustrated particularly in Figs. 13 to 27, inclusive. This device embodies the means for cutting off the strap from the source of supply and forming an interlocking joint between its overlapping ends which is disclosed in United States Letters Patent No. 2,375,769 granted May 15, 1945, on an application of William C. Childress and James M. Royal. The mechanism disclosed therein is substantially the same as the major portion embodied in the sealing device 75 and reference may be had to said Letters Patent for a more detailed description than is given here, it being understood that other forms of strap cutting and sealing devices may be employed in place of the one which is here illustrated and described.

The sealing device 75 illustrated in the drawings and described in said Letters Patent is adapted to employ an open channel-shaped seal 130 which is shown particularly in Fig. 2b where it is illustrated as having a back wall 130a and two flaring side walls 130b which are adapted to bend around and beneath the overlapping ends of the strap 65 during the operation of the sealing apparatus and to be partially sheared and deflected to form an interlocking joint. These seals are preferably provided on their side walls with punched projections 130c so that when they are arranged in a stack there will be a small area of contact between the walls of adjacent seals, thus providing the minimum of resistance to the sliding movement of the bottom seal from the stack of seals. The top walls of these seals are provided with centrally located apertures 130d so that they may be arranged in a stack for convenience in shipping them and inserting them in the magazine of the sealing device. This form of seal and the resulting package of seals are described and claimed in United States Letters Patent Nos. 2,062,098 and 2,062,099 granted November 24, 1936, on applications of Chester M. MacChesney. In the operation of the sealing device 75 the side walls 130b of the seal are bent beneath the overlapping strap ends and the sealing jaws of the tool are then operated to effect the shearing of the edges of the seal and the enclosed strap ends as shown at 130e in Fig. 2a. The portion of the metal between the adjacent shearing cuts is deflected to form projections 130f, thus furnishing interlocking shoulders which prevent relative separation of the strap ends. A similar joint could be formed by threading the strap ends through a tubular seal and then shearing and deflecting portions of the lateral edges of the assembled strap and seal instead of using the channel-shaped seal which has just been described. Also, other forms of tools could be employed in place of the sealing devices 75 to provide other forms of interlocking joints between the overlapping strap ends after the strap has been extended around the bale or bundle, drawn taut and then cut off from the source of supply.

In the form of sealing apparatus illustrated in Figs. 13 to 27, inclusive, the mechanism is carried by a frame or casting 135 having laterally extending flanges 135a and 135b which extend beneath the strap 65. On this frame 135 a forward gripping dog 136 is mounted on a pivot pin 137 carried by the frame 135 and this gripping dog has a serrated lower edge 136a adapted to engage the

upper side of the end portion 65a of the strap after the strap has been passed around the bale or bundle by the operation of the feeding device 60 and after the operator has taken the free end of the strap from its position above the housing 80 and extended it over the top of the bale and into position on the flange 135a beneath the gripping dog. This gripping dog 136 is normally moved into engagement with the strap on the flange 135a by a coil spring, not illustrated, and it is so constructed that the strap end 65a will slide freely beneath it upon being pushed toward the right as viewed in Fig. 13 although any tendency of the strap to move in the reverse direction will be resisted by the gripping of the dog 136.

In passing to the sealing device 75 from the feeding device 60, the strap passes through a longitudinal groove 136b which is formed in the gripping dog 136 and it then passes through the groove 138a of a guide member 138 which is mounted on the frame 135 above the flange 135a. From the guide member 138, the strap 65 extends over the flange 135b of the frame and thence into contact with the magnetic rollers 115 on the underside of the pressure platen 45, as previously described. Above the flange 135b there is mounted another gripping dog 140 which is pivoted on a pin 141 mounted in the frame and which is located in an inclined position so that its lower serrated gripping surface 140a will grip the strap when it is moved toward the right as viewed in Fig. 13 but will release the strap when it is moved in the opposite direction. The dog 140 is normally moved into engagement with the strap by coil spring 142 which is mounted in a recess in the underside of the upper end of the gripping dog with its lower end engaging a projection 143 carried by the frame.

After the strap 65 has been extended around the bale or bundle by the motor driven feeding device 60, the free end 65a thereof is pushed under the gripping dog 136 until its end engages a stop member 145 which, at that time, will have been positioned so that it will form an abutment for the end of the strap. After the strap is thus in a position encircling the bale or bundle with its end engaging the stop 145, the motor 102 of the associated feeding device 60 is reversed in direction so that it then pulls the strap in a direction opposite to that in which it has previously been fed, thereby taking up the slack in the strap and drawing it taut around the bale or bundle 46. During this operation the free end of the strap is securely held by the gripping dog 136, while the supply portion thereof runs freely beneath the gripping dog 140. When the strap has thus been drawn taut around the compressed bale or bundle, the gripping dog 140 is actuated as hereinafter described to cause it to grip the supply portion of the strap and other parts of the mechanism are operated to cut off the supply portion of the strap with an overlapping of the ends of the portion of the strap which extend around the bundle. After the overlapping of the ends has been effected the sealing mechanism is operated to feed a seal to a position where it may be caused to engage the overlapping strap ends preliminary to a further operation which forms the type of joint shown in Fig. 2a.

This sealing mechanism comprises a vertically extending seal magazine 147 on which there is slidably mounted a vertically movable sealing head 148 having pivotally mounted therein a pair of sealing jaws 150 which are capable of relative movement for first bending the side walls of the seal 130 beneath the overlapping strap ends and then cutting and deforming the edges of these parts to form the joint. The lowermost seal of the stack of seals 130 in the magazine 147 is adapted to be fed by a plunger 151 from the bottom of the magazine to a position between the jaws 150 when the sealing head 148 and the jaws are in the elevated positions shown in Fig. 13. At the beginning of the downward movement of the sealing head 148 and the jaws 150 to cause the seal to embrace the strap ends, a movable shearing blade 153 is moved

into position to cooperate with a stationary shearing blade 154 to cut off the supply portion of the strap in a position such that the strap end so formed will lie flush with the end of the seal in the joint about to be made.

This downward movement of the sealing head 148 and of the jaws 150 is effected by the sealing lever 155 which is pivoted by means of a shaft 156 on the sealing head 148. The shaft 156 also pivotally connects the lever 155 and the head 148 with a tilting frame 157 which is pivotally connected at its rear end by a hollow pin 158 with a supporting member 159 carried on the pivot pin 159a mounted in the bracket 160 secured to the frame 135. A block 161 is mounted to slide on the sealing lever 155 and this block is pivotally connected by a pin 162 with an operating lever 163 having its lower end pivoted at 164 on a lateral extension of the frame 135. This operating lever 163 is pivoted at an intermediate point 165 to a piston rod 166 which extends into a cylinder 167 where it is connected to a piston 168. This cylinder 167 is adapted to be operated by fluid pressure, such as compressed air or the like, and the rear end thereof is provided with a flange 167a which is pivoted at 169 to a bracket 170 fixed on the transverse frame member 51 of the pressure platen 43. When compressed air is admitted to the right-hand end of the cylinder 167, as viewed in Fig. 3, the piston rod 166 is actuated to move the lever 163 toward the left and thereby cause an upward and forward swinging of the tilting frame 157 about the member 158 with a resulting downward movement of the sealing head 148 and jaws 150. When compressed air is admitted to the forward end of the cylinder 167, the piston rod 166 is retracted and the parts are restored to the positions which they have in Fig. 13. Thus, by the operation of the piston 168 in the cylinder 167 the mechanism is actuated to cut off the strap from the source of supply, feed a seal to a position between the sealing jaws 150, actuate the sealing head 148 and the jaws to form an interlocking joint between the overlapping strap ends, and then to restore the parts to their initial positions wherein the jaws 150 may receive another seal 130 from the bottom of the magazine 147.

Referring now to the sealing mechanism actuated by the lever 155, the sealing head 148 comprises a hollow frame 171 mounted to slide on the magazine 147 through interlocking flanges, as shown in Fig. 17, so that the frame of the head 148 is capable of movement vertically toward and from a notch 135c in the base flange of the frame 135 above which the interlocking joint in the overlapping strap ends is formed. The frame 171 has a vertical passage 171d of rectangular cross section in which a plunger 174 has a sliding fit. This plunger is arranged to actuate the sealing jaws 150 which are pivotally mounted on pins 175 extending between the side plates 171a of the sealing frame. The upper arms of the jaws 150 are pivotally connected by pins 176 to links 177 which are connected at their upper ends by a common pivot pin 178 to the lower end of the plunger 174. The plunger 174 is normally moved to the upper position, shown in Fig. 20, by a pair of coil springs 179 which connect the plunger with a bar 180 attached to the upper end of the frame 171.

Each jaw 150 is made up of a plurality of plates or laminations comprising three bending dies 150b and two alternately arranged cutting or shearing dies 150c. The bending dies 150b are provided at their lower ends with undercut portions 150e located above the projecting hook portions 150f which terminate in registering projections 150g adapted to receive and support the edges of the side walls 130b of one of the channel-shaped seals 130 when this seal is fed from the magazine 147 by the feeding plunger 151 to a position between the jaws as shown in Fig. 20. The shearing dies 150c of each jaw are provided at their lower ends with cutting or shearing edges 150h which are spaced inwardly from and between the

projecting hook portions 150f of the bending dies so that upon relative movement of the lower ends of the two jaws 150 toward each other, the bending dies 150b first bend the side walls of the seal downwardly and inwardly about the overlapping strap ends with the edges of the strap and seal extending into the undercut recesses 150c, and with the completion of this relative movement of the jaws, the cutting edges of the shearing dies come into action to shear the lateral edges of the strap and seal and to deflect the intervening portions of the metal to form the type of joint shown in Fig. 2a.

On their lower inner sides the jaws 150 are provided with arcuate surfaces which are concentric with the pivot pins 175 and between these surfaces there is positioned a saddle member 183 (Figs. 19 and 20) which is actuated by springs 184 seated in a block 185 extending between the sides of the frame 171 so that it engages the back wall 130a of the seal and holds the edge of the side walls of the seal in engagement with the extremities 150g of the jaws when the sealing head is in the elevated position shown in Fig. 20. The saddle member 183 is adapted to move slightly against the compression of the springs 184 during the closing of the jaws on the seal.

The downward movement of the plunger 174 against the action of the springs 179 is effected by a pinion 156a, formed integrally with the shaft 156 which is journaled in bearings formed in ears projecting from the side plates of the frame 171, as shown in Fig. 17, and arranged to mesh with the rack bar 174a formed on the vertical face of the plunger. The shaft 156 has the form shown particularly in Fig. 24, being provided at one side of the pinion with a cylindrical portion 156b which is journaled in one of the ears projecting from the frame 171 and at the other side of the pinion with another cylindrical portion 156c which is journaled in a bushing 186 secured in the other ear projecting from that frame.

The shaft 156 is adapted to turn in its bearings to effect vertical movement of the plunger 174 and it also serves as the means through which a vertical motion is imparted to the head 148 independently of the movement of the plunger. The head 148 is directly supported by the tilting frame 157, previously referred to, which has side members which are apertured for pivotal engagement with the portion 156b of the shaft 156 and with the bushing 186, as shown in Fig. 17, so that a swinging movement of the tilting frame is adapted to raise or lower the head 148 and its frame 171.

The side members of the tilting frame 157 receive between them at their rear ends the upper end of the pivoted supporting member 159 to which they are pivotally connected by the previously mentioned hollow pin 158. The supporting member has a boss 159c at its upper end in which the hollow pin or bushing 158 is secured by a set screw 187 engaging an annular groove in the bushing. The tilting frame 157 is thus capable of pivotal movement about the upper end of the supporting member 159 and the supporting member is capable of pivotal movement about the pin 159a to allow the frame 171 of the head 148 to move vertically toward and from the overlapping strap ends.

After the member 159 has swung toward the left, as viewed in Figs. 13 and 18, and the frame 157 has swung downwardly to position the seal 130 carried by the head on the overlapping strap ends, the shaft 156 is turned to cause the pinion 156a to move the plunger 174 downwardly and thereby actuate the jaws 150 to form an interlocking joint. This turning of the shaft 156, and the reverse rotation thereof, are effected by the sealing lever 155 actuated by the cylinder 167. The lever 155 is mounted upon the forward extremity 156d of the shaft (see Fig. 17), which is recessed at this point to provide a plurality of longitudinally extending ribs 156e which are spaced apart circumferentially of the shaft and which are adapted to receive between them a plurality of longitudinally extending splines or keys 155c. These keys

are formed in the bore of the hub 155a of the sealing lever and when this lever is released from the tilting frame 157, as hereinafter described, the ribs 156e of the shaft are adapted to coact with the keys or splines 155c on the lever to form a driving connection which is made use of in effecting a downward movement of the plunger 174 and a corresponding closing movement of the jaws 150.

Another driving connection between the sealing lever 155 and the shaft 156 is provided for permitting the turning of the shaft by the lever to separate the jaws at the conclusion of the sealing operation, since this cannot be done by the ribs 156e and the keys 155c on account of the lost motion between these parts when the lever is moved toward the right as viewed in Fig. 13. This additional means comprises a locking plate 188 mounted on an extremity of the shaft 156 and seating against the outer face of the hub portion 155a of the lever 155. The locking plate and the lever are secured on the shaft by a nut 189 which engages the threaded extremity of the shaft and seats against a washer 190 where it is secured by a set screw 191.

The locking plate 188 is of pear-shaped form, the projecting arm thereof being provided with an aperture 188a of sufficient size to receive one rounded extremity of a locking pin 194 which occupies a cylindrical passageway 155b extending through the hub of the lever. On the inner side of the hub of the lever, another locking plate 195 is journaled on the projecting end of the bushing 186 and secured to the face of the adjacent tilting frame 157 by means of a pin 196, as shown in Fig. 22. The plate 195 is provided with a recess 195a adapted to register with the passageway 155b in the hub of the lever and adapted to receive the inner rounded extremity of the locking pin 194. The recesses 188a and 195a are tapered so that the pressure exerted on the adjacent end of the pin by relative movement of the lever and the locking plate in which the aperture is formed will tend to wedge the pin 194 away from the locking plate into the aperture 155b.

The locking plate 188 has keyways 188b, shown in Fig. 26, which engage the extremities 156g of the ribs 156c formed on the shaft 156. When the pin 194 is moved outwardly to engage the recess 188a, a driving connection is established between the locking plate 188 and the lever 155 so that movement of the lever will then turn the shaft in its bearings. When the locking pin 194 is moved inwardly into engagement with the recess 195a in the locking plate 195 which is mounted to swing with the tilting frame 157, the outer end of the lever will be out of engagement with the recess 188a and the lever 155 may then be swung about its pivot without turning the shaft 156. This locking connection formed by the pin 194 is made use of only for rotating the shaft 156 to separate the jaws, but it is established in the course of the movement of the lever toward the left, as viewed in Fig. 13, before the closing of the jaws has been completed.

The lever 155 and its hub 155a are provided with an integral depending flange 155d of arcuate form and a lug 155e projecting from the face of this flange has adjustably mounted therein a threaded stud 197 which is secured in adjusted position by a lock nut 198. The end of this stud below the nut 198 is adapted to engage a hard metal stop member 199 which is secured in a projecting flange 171j formed on the frame 171 of the head 148. When the lever 155 is swung downwardly and toward the right, as viewed in Fig. 13, the stud 197 is adapted to engage the stop member 199 to limit the movement of the lever and the corresponding upward movement of the head 148. By adjusting the position of the stud 197 in the lug 155e, the extreme upper position of the head may be precisely located so that it will properly receive a seal from the magazine 147 when the seal is fed by the plunger 151.

The lever 155 is provided adjacent the flange 155d with a lug 155f having a flat lower face adapted to engage a projecting lug 157c formed on the tilting frame 157. After a predetermined movement of the lever 155 from the position shown by dotted lines in Fig. 21 to the position shown by full lines in that figure, the lug 155f engages the lug 157c to cause a direct actuation of the tilting frame 157 by the lever, thereby elevating the head 148 from its lower position. When the lever 155 is in the position shown by dotted lines in Fig. 21, which corresponds to the position wherein the shaft 156 has been actuated to lower the plunger 174 and effect a relative movement of the sealing jaws 150, a boss 155g formed on the lever engages the surface 171k formed on the upper end of the flange 171j, thereby limiting the movement of the jaws 150 in closing upon each other. This action is supplemented by the engagement of the lower end of the plunger 174 with the block carried by the sealing head for supporting the springs 184.

Assuming that the head 148 has been elevated and that the lever 155 occupies its extreme right-hand position as shown in Fig. 13 and that it is desired to lower the head from this elevated position shown in Fig. 13, it is necessary to establish a driving connection between the lever 155 and the frame 157 so that this frame may be swung about the hollow pin or bushing 158 and the supporting member 159 moves forwardly about its pivot 159a, without causing rotation of the shaft 156 which actuates the jaws. This locking connection is normally established by a locking pin 200, shown particularly in Figs. 17 and 22, which is mounted within the hollow pin 158. The pin 200 is provided at one end with an enlarged cylindrical head 200a which is adapted to fit within a cup-shaped locking member 201 mounted in a recess in the inner face of the lever 155. At its other end, the locking pin 200 is provided with an enlarged cylindrical portion 200b which is located within the enlarged end 158a of the hollow pin which seats against the rear face of the tilting frame 157. The enlarged portion 200b of the locking pin has formed integrally therewith an annular flange 200c constructed in the form of a double truncated cone. The end face 200d of the pin 200 normally occupies a position in proximity to the inner face of the vertical frame member 135p, as shown in Fig. 17, and the flange 200c then abuts against the enlarged end 158a of the hollow pin. When the pin 200 is in this position, the extremity 200a thereof engages the cup-shaped locking member 201, so that when the lever 155 is swung upwardly and toward the left as viewed in Figs. 13 and 21, the tilting frame 157 will be swung downwardly about the hollow pin 158 and the supporting member 159 will swing toward the left, as viewed in Fig. 18, about the hollow pin 158. When the lever 155 reaches a predetermined position corresponding to the lower position of the sealing head 148 which positions a seal on the overlapping strap ends, one of the annular inclined faces of the flange 200c on the pin 200 engages the inclined face 203a of a stationary cam 203 which is secured to the frame member 135p. The inclined face 203a forces the flange 200c into a tapered recess 135u formed in the member 135p and this endwise movement of the pin 200 withdraws the extremity 200a thereof from the cup-shaped locking member 201 mounted on the sealing lever so that this lever 155 is then free to move about its pivot 159 on the shaft 156 independently of the tilting frame 157 which then remains stationary during further movement of the lever 129 in the same direction.

During the movement of the sealing lever 155 toward the left as viewed in Figs. 13 and 18 to the point where the pin 200 moves out of engagement with the locking member 201 and into engagement with the recess 135u, the locking pin 194 mounted in the hub of this lever occupies its inner position and the outer end of this pin 70 moves within the flat inner face of the outer locking

member 188 but, when this point in the movement of the lever 155 is reached, the pin 194 registers with the recess 188a in the locking plate 188 and further pressure on the lever 155 which has then been released by the locking pin 200 causes the inner end of the pin 194 to be wedged outwardly by the inclined annular face of the recess 195a formed in the inner locking plate 195. The pin 194 then moves outwardly until the outer rounded extremity thereof fully enters the recess 188a, whereupon the inner end of the pin 194 moves past the flat outer face of the inner plate 195. A driving connection is thus established between the lever 155 and the shaft 156 through the pin 194 and the plate 188 and, at the same time, another driving connection is established between the lever 155 and the shaft 156 through the splines 156e and the casing 155c which have previously been described. The later driving connection is relied upon for rotating the shaft 156 to effect the downward movement of the plunger 174 and the closing of the jaws 150, and the driving connection formed by the pin 194 is established primarily for subsequently opening the jaws after the sealing operation has been completed. When the sealing lever 155 has completed this movement of the plunger 174 the lever occupies the position shown by dotted lines in Fig. 21 and the jaws 150 are then closed upon the overlapping strap ends as shown in that figure.

During the initial stage of the return movement of the lever 155 toward the right as viewed in Fig. 21, the locking connection established between the pin 194 and the locking plate 188 is relied upon for turning the shaft 156 and releasing the jaws 150 from the completed strap joint, an operation which is assisted by the action of the coil springs 179 previously referred to. After a predetermined pivotal movement of the lever 155 toward the right, the lug 155f on the lever engages the lug 157c carried by the tilting frame, as shown by full lines in Fig. 21, so that further movement in the same direction causes an elevation of the tilting frame 157 about the hollow pin 153, thus elevating the head 148 from its lower position. At the beginning of this pivotal movement of the tilting frame 157, the pressure of the inclined face of the flange 280c on the locking pin 200 against the inclined face of the recess 135u in the stationary frame member will cause the pin 200 to be moved in a forward direction into engagement with the cup-shaped member 201 carried by the lever 155 so that a driving connection between the lever and the tilting frame is thereby established in readiness for the next movement of the sealing lever 155 toward the left as viewed in Fig. 21.

Referring now to the seal feeding means which includes the feeding plunger 151, this mechanism is illustrated particularly in Figs. 17 and 18 where the plunger 151 is shown as being mounted to slide on a horizontal flange 135h of the frame within a guideway 204b which is formed within an auxiliary housing 204 secured to the frame 135. The plunger 151 is provided at its extremity adjacent the seal magazine 147 with converging side faces 151a which are directed toward the position where the seals are fed between the jaws 150 of the sealing head 148. The forward extremity of the plunger 151 is provided with an upturned flange 151c which is adapted to engage the top wall of the lowermost seal of the stack of seals in the magazine so that when the plunger is actuated this seal will be projected into position between the jaws without at the same time effecting any movement of the next adjacent seal. To insure against any possible engagement with this next seal, the upper side of the plunger 151 is provided with a longitudinal recess or groove 151d. The movement of the seal into position between the jaws is arrested by the engagement of the end of the seal with the flange 171m which projects downwardly from the side wall of the frame 171 as illustrated in Fig. 18. After the seal has been fed to this position, the plunger 151 is returned to its retracted posi-

tion and the head 148 is then lowered to place the seal over the overlapping strap ends as previously described.

The movement of the seal feeding plunger 151 is effected by a lever arm 206a which is formed as a part of a combination lever 206 having its hub pivoted on a pin or bolt 207 which is secured in fixed position in the auxiliary housing 204. The lever arm 206a is provided at its lower end with a spherical extremity 206b which engages an aperture 151e formed in the plunger so that a reciprocatory movement of the plunger is effected by the angular movement of the lever arm. The combination lever 206 is provided with another arm 206c and a coil spring 208 attached to this arm at one end and having its other end attached to a lug carried by the housing 204 which serves normally to actuate the lever 206 about the pin 207 to cause a feeding movement of the plunger 151 toward the right as viewed in Fig. 18.

The action of the spring 208 is normally restrained and the plunger 151 is held in its retracted position by the operation of certain latch mechanism comprising a lever arm 206d which is formed integrally with the hub of the lever 136 and which has mounted on the lower end thereof a rearwardly projecting pin 209 shown particularly in Figs. 18 and 27. This pin has pivoted thereon a latch member 210 having the form shown particularly in Fig. 28 which has an arm 210a extending toward the left as viewed in Fig. 18 and terminating in a transverse flange 210b carrying an upwardly extending tooth 210c provided with an arcuate upper surface 210d. The tooth 210c is adapted to project upwardly behind the head 211a of a stationary detent pin 211 which has an adjustable threaded engagement with the end wall of the housing 204 where it is secured in adjusted position by a set screw 212. The arm 210a of the latch member is connected to a coil spring 214 which extends upwardly with its other extremity connected to an arm 206e formed on the combination lever 206. This coil spring 214 tends normally to move the arm 210a of the latch member upwardly so that the tooth 210c is retained behind the head 211a of the stationary detent. The latch member 210 thus operates normally through the coil spring 214 to maintain the seal feeding plunger 151 in its retracted position. The extent of the upward movement of the arm 210a of the latch member under the influence of the spring 211 is limited by the engagement with the hub of the lever 206 of a projecting arm 210f which is formed on the upper part of the latch member and which normally occupies the position shown in Fig. 27. The head 211a of the stationary detent is provided with an end face in the form of a truncated cone which is adapted to engage the tooth 210c of the latch member when the lever 206 is swung from the position shown in Fig. 18 to the position shown in Fig. 27, with the result that the tooth 210c snaps under the head of the detent and automatically assumes the position shown in Fig. 27.

The release of the latch member 210 from the detent 211, to permit the feeding movement of the plunger 151 under the influence of the spring 208, is effected by the movable head 148 through a link 215. For this purpose, the link 215 is connected at its upper end to the shaft 156 which moves with the sealing head. This upper end of the link has formed therein a longitudinal slot 215a which is slidably engaged by a block 217 having a non-circular aperture therein to receive the flattened extremity 156h of the shaft. A pair of washers 218 are mounted on the shaft on opposite sides of the block 217 and they overlap the link 215 around the slot 215a, as illustrated in Fig. 17. These parts are secured in assembled relationship by a nut 219 engaging the threaded end of the shaft 156. The block 217 has some movement longitudinally of the slot 215a in order to allow for vertical movement of the shaft 156 at an angle to the longitudinal axis of the link but when the head 148 approaches the upper limit of its travel, the block 217

engages the upper end of the slot and the link 215 is thereby moved endwise to cause the lower part thereof to trip the latch 210 and thereby release the plunger 151 which is then actuated by the spring 208 to feed a seal from the magazine to a position between the jaws.

The lower end of the link 215 has a longitudinal slot 215b which is slidably engaged by the previously mentioned pin 209 on which the latch member 210 is mounted. The link 215 is further provided at its lower end with a depending arm 215c having a transverse flange 215d which projects into the plane of the body portion of the latch member 210. When the link 215 is moved upwardly and toward the right from the position shown in Fig. 27, by the upward movement of the head 148, the flange 215d on the link will engage the depending arm 210g of the latch member and rock the latch member about its pivot on the pin 209 against the tension of the spring 214, with the result that the tooth 210c is released from the head of the detent 211 to permit the seal feeding movement of the plunger 151 which has just been referred to.

When this seal feeding movement is completed, the plunger 151 will occupy the position shown in Fig. 18 and the pin 209 will have moved to the upper end of the slot 215b in the link 215, while at the same time the link will have been forced upwardly so that the block 217 will occupy the lower end of the slot 215a in the upper part of the link. Then, upon the succeeding downward movement of the head 148, the initial movement actuates the link 215 to start a reverse movement of the plunger 151 before the extremity of this plunger is engaged by the side plate of the head 171 which is provided at its lower end with an inclined surface 171p, shown in Fig. 18, which will wedge the feeding plunger out of the way in the event that it has not been moved when the head 148 reaches the lower end of its travel. The latch member 210 then snaps back into engagement with the detent 211 so that the spring 208 is again put under tension in readiness for a succeeding feeding movement of the plunger.

In addition to controlling the actuation of the seal feeding mechanism, the movable head 148 also controls the actuation of the mechanism by which the supply portion of the strap is cut off and the two ends of the strap placed in proximity to each other in readiness to receive the seal. This cutting mechanism which is shown particularly in Figs. 13, 17, 18 and 20 comprises the movable shearing blade 153 and the blade 154 which is stationary during the shearing operation, both of which blades have previously been mentioned. Both blades are carried by a lever 220 which is pivoted on a bolt 221 mounted in a boss carried by the upright portion 135p of the frame, as shown in Fig. 20. The lever 220 is provided at its lower end with a pair of spaced flanges 220b which receive between them the enlarged rear extremities of the shearing blades 153 and 154. These extremities of the blades are apertured for engagement by a bolt 222 which secures them in position and the blade 154 is secured in fixed position to the lever 220 by means of a pin 223, while the other blade 153 is free to turn about the bolt during the shearing operation. When the blades are in the shearing position shown in Fig. 20, the lower shearing blade 154 is located slightly above the base flange 135a of the frame so that the free end 65a of the strap may pass thereunder to the stop member 145. The two blades are provided with sharp cutting edges in the region where they overlap the supply portion of the strap 65 so that, upon downward movement of the blade 153, the strap will be cut off. This cutting movement is effected by a lug 153c formed upon the upper shear blade which is engaged by a cam surface 171p on the side plate of the frame of the head 148 when this head is moved downwardly so that the movable shearing blade is thereby actuated to cut the strap.

Inasmuch as the shearing blades 153 and 154 occupy

a position directly beneath the head 148 during the shearing operation, it is necessary to effect a lateral movement of both shearing blades in order to get them out of the way of the head at the time that this head moves from the position shown in Figs. 1 and 20 to the position shown in Fig. 21 and, for this purpose, the lever 220 which extends upwardly at the rear of the frame 135 is automatically rocked about its pivot 221 by the movement of the head. The upwardly extending arm 220c of the blade supporting lever is provided with a forwardly extending boss 220d in which there is secured a pin 225 adapted to travel between two cam shaped guide flanges 171r which are formed on the rear faces of the side plates of the head as shown in Figs. 17 and 20. These cam flanges 171r have upper and lower vertical portions which extend parallel to each other and these are connected by parallel inclined portions 171s. During the initial portion of the downward movement of the head 148 the pin 225 travels in the slot between the upper vertical portions of the flanges 171r but, after this downward movement of the head has proceeded to the point where the blade 153 has been moved downwardly to a sufficient extent to shear the supply portion of the strap, the pin engages the inclined portions 171s of the guide flanges and this causes the lever 220 to be rocked about its pivot 221 with the result that both of the blades 153 and 154 are moved toward the left as viewed in Fig. 13, until they are carried out of the path of movement of the head 148 which then continues its downward movement until the seal positioned between the jaws 150 is seated upon the overlapping strap ends, the upper sheared extremity of the strap which has just been cut off by the blades being moved downwardly by the seal until it lies upon the uppermost extremity of the strap. When this operation has been completed, the parts occupy the relative positions shown in Fig. 21 with the shearing blades located at one side of the jaws and associated parts of the head.

Upon the reverse movement of the shearing lever 155 with the consequent upward movement of the head 148, the reverse operations are effected with respect to the lever 220 and the shearing blades are carried back to a position beneath the elevated shearing head, the movable shearing blade 153 being then automatically elevated to the position shown in Fig. 20 by the operation of a link 226 which is provided at its lower end with a slot 226a engaged by a headed pin 153e formed on the end of the movable shearing blade. The upper end of the link 226 is provided with a slot 226b which is engaged by a pin 227 secured to the frame 171 of the shearing head 50 so that the elevation of the head causes this link to elevate the blade.

The means for actuating and controlling the gripping dogs 136 and 140 will now be described, referring first to the gripping dog 140 which is adapted to grip the supply portion of the strap 65 and hold it against the flange 135b of the frame. As previously described, this dog is normally held in this gripping position by the spring 142 but, when the lever 163 is moved to the extreme right-hand position, as shown in Fig. 13, corresponding to the elevated position of the sealing head 148, the upper end of the dog 140 is engaged by an arm 163a projecting laterally from the lever and this end of the lever is pressed downwardly against the compression of the spring 142 and its serrated gripping surface 140a is elevated away from the flange 135b so that the supply portion of the strap may pass freely beneath the gripping dog while it is being fed around the bale or bundle by the associated feeding device 60.

The forward gripping dog 136 of each sealing device is normally moved into the gripping position shown in Fig. 13 by a coil spring (not shown) which is seated in a recess in the gripping dog and engages a part of the frame 135 but this dog may be elevated out of gripping position either manually or by compressed air oper-

ated means. The manually operated means comprises a lever 230 (Figs. 3, 13, 15 and 29) which is pivoted on the pin 137 on which the gripping dog is mounted and extending upwardly therefrom. This lever has a U-shaped lateral extension 230a terminating in a rearwardly extending portion 230b which engages the forward face of the gripping dog 136 below the level of the pivot 137. The upper end of the lever 230 is pivotally connected to a rod 231 which extends forwardly with its other end pivotally connected to one arm 232a of a bell crank lever 232 pivoted on a bracket 233 carried by a bracket mounted on the transverse frame member 52 of the pressure platen 45. The other arm 232b of this bell crank lever extends forwardly for engagement by the hand of the operator so that if the occasion arises the gripping dog 136 may be quickly lifted from its gripping position independently of the fluid pressure operated means for effecting this release.

This fluid pressure operated means comprises an upwardly extending lever 235 which is pivoted on the extremity of the pin 137, in front of the gripping dog 136 as viewed in Fig. 13, and which is provided at its lower end with a lateral extension 235a extending beneath a shoulder 136c formed on the gripping dog as an extension of the top wall of the strap receiving slot 136b. The lever 235 is pivotally connected at its upper end to a rod 236 (Figs. 3 and 13) which extends forwardly and is pivoted at its other end to a crank arm 237 fixed on a shaft 238. This shaft extends across the front end of the pressure platen 45 and is journaled in bearings carried thereby. A lever 239 is fixed on one end of this shaft (Fig. 8) and its upper end is pivotally connected through a link 240 to a piston rod 241 which extends into a cylinder 242 where a piston 243 is secured thereon to be actuated by compressed air. When compressed air is admitted to the left-hand end of this cylinder, as viewed in Fig. 8, the shaft 238 is turned to actuate the lever 235 and thereby elevate the gripping dog 136 from its gripping position against the compression of its actuating spring. When the compressed air is shut off from the end of the cylinder 242 just mentioned and admitted to the other end thereof, the gripping dog 136 returns to gripping position under the influence of its spring.

The lever 230 which is manually actuated to release the dog 136 has a depending crank arm 230c (Figs. 13 and 29) which is slotted at its free end for connection by a pivot pin 244 to one end of a sliding bar 245 mounted to travel in a guideway extending longitudinally of the frame 135. As shown in Figs. 12 and 15, the sliding bar 245 is provided at its other end with a cam portion 245a adapted to contact the end of the strap stopping lever 145, previously referred to which is pivotally connected at an intermediate point by a pin 246 to a pair of flanges formed on the frame 135. The lever 145 is mounted in a transverse recess formed in the frame 135 and its forward end 145a extends normally beneath a guide slot 135t formed in the base of the frame through which the strap is adapted to extend as shown in Figs. 12 and 13. A spring 247 is seated in a recess formed in the frame 135 and bears against the upper side of the stop lever 145 to force it normally to the position shown in Fig. 12 where it does not obstruct the slot 135t. When the bell crank lever 232 is actuated to move the gripping dog 136 out of its gripping position, the sliding bar 245 is at the same time actuated by the crank arm 230c to move toward the right, as viewed in Fig. 15, with the result that the inclined wedging surface of the cam portion 245a engages the end 145b of the stop lever and depresses this portion so that the portion 145a is elevated to obstruct the slot 135t and thereby provide a stop for the free end 65a of the strap as shown in Fig. 13 which at that time is fed into the sealing device 75 by hand after having been passed around the bale or bundle 46 by the power driven feeding device 60.

When the strap has been passed around the bundle and its end positioned against the stop lever 145, the gripping dog 136 is released to grip the free end of the strap and the feeding device 60 is then reversed to draw the strap taut around the compressed bundle, whereupon the lever 163 is actuated by admitting compressed air to the cylinder 167 to operate the shearing and sealing mechanism. The initial movement of the lever 163 causes its arm 163a to release the gripping dog 140 which then moves to its gripping position under the influence of the spring 142 to hold the supply portion of the strap against the flange 135b of the frame so that this supply portion may then be cut off by the shearing blades 153 and 154 upon further movement of the lever 163 and of the sealing lever 155.

When the motion of the lever 155 has been continued to cut off the supply portion of the strap and to unite its overlapping ends by applying a seal thereto, the taut and sealed strap is displaced from the sealing device 75 by ejecting mechanism which is shown particularly in Figs. 7, 8, 9, 10 and 16. One unit of this ejecting mechanism is provided for each sealing device 75 although the several units have common actuating means. Each unit comprises an ejector bar 250 which is slidable laterally of the pressure platen 45, the one shown in Fig. 7 being that which is located adjacent the left-hand side of the pressure platen as viewed in Fig. 1. Each ejector bar 250 includes a bar 251 extending inwardly from the forward end of the pressure platen and provided on its underside with a longitudinal strap receiving groove 251a having a flared mouth 251b to facilitate the insertion of the strap after it has been passed around the bundle. This bar 251 is provided at its inner end with a projection 251c which is secured to an intermediate bar 252 mounted on its outer side. The bar 252 is secured at its inner end to the projecting extremity of one side bar 253a of an auxiliary frame 253 which carries the bearings for the magnetic rollers 115 beneath which the strap 65 travels over the top of the bundle during the feeding operation. The formation of the bars 251 and 253a and the spacing of these bars with their ends in registry with a notch 252a in the intermediate bar provides an opening 250a of stepped form in the region above the strap where the strapping device 75 is located and where the strap joint is formed. The sealing device is located partially over this opening and partly over a rectangular notch 254a formed in a supporting plate 254 which extends longitudinally of the pressure platen 45 between the transverse frame members 51 and 52. The strapping device is secured to the plate 254 in this location.

The ejecting bar 250 is mounted between the plate 254 and another plate 255 which also extends between the transverse frame members 51 and 52, being spaced from the plate 254 a distance greater than the width of the ejecting bar and having a notch 255a therein of sufficient size to accommodate the intermediate bar 252. The ejecting bar 250 is adapted to be moved sidewise across the gap between the plates 254 and 255 and when it moves away from the observer as viewed in Fig. 7, the wall 251c of the groove 251a and a flange 253b on the roller frame 253 engage the edge of the taut strap and push it out of engagement with the flanges 135a and 135b and other parts of the sealing device 75.

All of the ejecting bars 250 for the several sealing devices 75 which are embodied in the machine are actuated simultaneously by common actuating means. For this purpose each bar 251 is secured by studs 257 to an actuating bar 258 and each auxiliary frame 253 is secured by studs 259 to an actuating bar 260. The two bars 258 and 260 extend transversely of the pressure platen at the front and rear ends thereof being slidably mounted on the plates 254 and 255 and retained in position by the guide members 261 which are secured to these plates by studs 262 as shown in Figs. 7 and 10.

The ends of the actuating bars 258 and 260 at the

left side of the machine, as viewed in Fig. 1, are pivotally connected by pins 263 to links 264 which are in turn pivotally connected by pins 265 to crank arms 266 secured on a shaft 267. This shaft extends along the side of the pressure platen 45 and is journaled in bearing blocks 268 secured to the adjacent side plate 50. At an intermediate point, a crank arm 270 is secured on the shaft 267 with its outer end pivotally connected by a pin 271 with a piston rod 272 which is secured to a piston 273 within a cylinder 275 to either end of which compressed air may be admitted. This cylinder is provided at its sides with supporting trunnions 276 which are journaled in brackets 277 mounted on the side plate 50 so that the cylinder may rock and adjust itself to the motion of the crank arm 270. When the piston 272 is projected from the cylinder 275 by air pressure the bars 258 and 260 are actuated to operate all of the ejecting bars 250 through strap ejecting strokes and when the piston rod is withdrawn into the cylinder 275, the ejecting bars are withdrawn to their normal positions wherein the guide channels 251a may receive the straps of the next strapping operation.

Before describing the fluid pressure system and the electric circuit by which the operations of various parts of the machine are effected and controlled, the successive steps which are carried out by the machine in the compression and binding of a bundle or package will be summarized. After the pressure platen 45 has been elevated to a sufficient extent, the bale or bundle to be bound is moved over the rollers 47 to the binding position, whereupon the pressure platen is lowered by the admission of compressed air to the cylinder 62 and the downward movement of the pressure platen is then continued until the bundle 46 has been compressed to a point where the pressure exerted by the air in the cylinder 62 is equalized. This air pressure is maintained during the subsequent binding operations which are initiated by admitting compressed air to the motors 102 which then operate to cause the feeding device 60 to withdraw a strap from the source of supply and feed it through the guide channels 136b, 138a and 135a of the sealing device 75, beneath the gripping dog 140 of that device, thence in contact with the undersides of the magnetic rollers 115, past the magnetic rollers 117 and 120 and through the portions 70b and 70C of the strap guide channel until the extremity 65a of the strap projects upwardly at the forward side of the machine as shown in Fig. 3. The operator then grasps this extremity of the strap and bends it over toward the pressure platen, whereupon it is passed beneath the sealing device 60 and then under the gripping dog 136 and the guide member 138 until the free end thereof engages the stop member 145 which will have been held in elevated position during this operation, along with the gripping dog 136, by pressure applied manually to the bell crank lever 232. When the strap is in the position just referred to with its extremity against the stop member 145, the bell crank lever 232 is released by the operator so that the supply portion of the strap is then automatically gripped by the gripping dog 136, while the supply portion thereof is free to pass beneath the gripping dog 140 which is held in elevated position by the lever 163. The driving motor 102 for the feeding mechanism is then reversed in order to pull the strap in the reverse direction and draw it taut around the bale or bundle 46. When the taut condition has been reached, the parts are in readiness for securing the ends of the strap together and this is effected by admitting compressed air to the associated cylinder 167 to cause the actuation of the lever 163 and the sealing lever 155. Upon the initial movement of the lever 163, the gripping dog 149 is released so that its spring 142 causes it automatically to grip the supply portion of the strap and the supply of air to the motor 102 may then be shut off since the strap will be held taut by the gripping dogs 136 and 141 during the continued movement of the sealing lever 155. When this lever has effected the

cutting off of the supply portion of the strap by the actuation of the cutting blades 153 and 154, the sealing operation is completed and, the gripping dog 140 then having been elevated by the movement of the lever 163 to the position shown in Fig. 13 and the gripping dog 136 having been elevated by the admission of compressed air to the cylinder 242, the ejecting bar 250 is operated to eject the strap from its position over the flanges 135a and 135b of the sealing device. This operation is effected by the admission of compressed air to the cylinder 275. When the strap has been released from the sealing device, the ejecting bar may be restored to its initial position and the pressure platen 45 may be elevated so that the bound bale or bundle may then be moved over the rollers 47 on to a conveyor. The sequence of operation which has just been described for a single bale or bundle applies also to the operation of two or more feeding devices, sealing devices, and other parts for applying a plurality of straps around the same bale or bundle.

20 The compressed air system by which the cylinders 62, 167, 242 and 275, and the motors 102 are actuated is illustrated diagrammatically in Fig. 30 where a common supply pipe 280 is shown as being connected through air filters 281 and a manually operated valve 282 to a supply conduit 283 leading from an air compressor or other source of compressed air supply. From the pipe 280, an air line 284 leads to a solenoid operated valve 285 having two solenoids 285a and 285b. From one end of this solenoid operated valve, an air line 286 leads to branch pipes 287 which extend to the lower ends of the cylinders 62 by which the movements of the pressure platen 45 are effected through the piston rods 61. Another air line 288 leads from the valve 285 through a manually operated valve 289 to the branch pipes 290 which extend to the upper ends of the cylinder 62. From the valve 285 an exhaust pipe 291 leads to the atmosphere. The solenoid valve 285 is provided with a plunger, not shown, which is actuated to open and close the various ports leading to the pipes connected thereto upon actuation of the solenoids by the electric circuit hereinafter described. When the solenoid 285a is elevated, the air line 284 is connected through the solenoid valve 285 to the air line 286 and the air line 288 is connected to the exhaust line 291. In this condition, air under pressure passes to the lower ends of the cylinder 62 to cause the elevation of the pressure platen 45 by the piston rods 61. At the same time air is exhausted from the upper ends of the cylinders 62 through the lines 290, 288 and 291 to the atmosphere. When the solenoid 285a is deenergized and the other solenoid 285b is energized, the air line 284 is connected through the valve 285 to the air line 288 and the air line 286 is connected to the exhaust line 291. Air then flows under pressure from the air line 280 through the line 284 and the lines 288 and 290 to the upper ends of the cylinder 62 while at the same time air exhausts from the lower ends of the cylinders through the air lines 287, 286 and 291. The piston rods 61 are then retracted to lower the platen 45 and effect the compression of the bale or bundle 46. When neither of the solenoids 285a or 285b is energized, the valve 285 remains in a neutral position whereby the air line 291 is closed and the supply line 284 is connected to both of the lines 286 and 288 so that the piston rods 61 are held stationary with the pressure platen in the fixed position to which it has been moved, a condition which prevails when the bale or bundle is being strapped after it has been compressed. The solenoids 285a and 285b are connected so that they are capable of being operated successively but not simultaneously.

70 The air cylinders 167, which operate through their pistons 168 and piston rods 166 to actuate the levers 163 of the sealing devices are supplied with compressed air from the line 280 through a line 295 which extends to a solenoid operated valve 296 having a solenoid 296a at one end thereof and a spring return device 296b at its other end. From the valve 296 an air line 297 leads to

three branch lines 298, 299 and 300 which extend through solenoid operated valves 301, 302 and 303 to the rear ends of the cylinders 167. These valves have solenoids 301a, 302a and 303a, respectively. From the solenoid valve 296 another line 304 leads through a three-way manually operated valve 305 to the branch lines 306, 307 and 308 which extend to the forward ends of the cylinders 167. An exhaust line 309 also leads from the solenoid valve 296 to the atmosphere. When the solenoid 296a is energized the plunger in the solenoid valve 296 is positioned so that air under pressure from the line 295 passes through the lines 297, 298, 299 and 300 into the inner or rear ends of the air cylinders 167 so that the pistons 168 are pushed forwardly to cause the piston rods 166 to actuate the levers 163 while at the same time air flows from the other ends of the cylinders and is exhausted through the lines 304 and 309. Thus, the sealing levers 155 are actuated to cut off the strap and to form a joint between each pair of overlapping strap ends. After the solenoid 296a is deenergized, the spring return 296b causes the plunger in the valve 296 to return to its initial position whereby the air line 295 is connected to the air line 304 and the air line 297 is connected to the exhaust line 309. When this connection has been established, the pistons 168 are retracted to their original positions as air under pressure passes through the lines 295, 304 and the branch lines 306, 307 and 308 into the forward ends of the cylinders 167. At the same time, the air is exhausted from the other ends of the cylinders 167 through the solenoid valves 301, 302 and 303, the branch lines 298, 299 and 300, the line 297 and the exhaust line 309.

The solenoid valves 301, 302 and 303 are capable of being operated selectively by means of their solenoids and individual electric switches so that one or all of them can be closed to prevent air under pressure from entering any one of the air cylinders 167, an arrangement which is desirable when fewer than three straps are to be applied to the bundle at the same time. The three-way valve 305 is provided in the line 304 with an outlet 305a so that air from the rear ends of the air cylinders 167 may be exhausted to the atmosphere when this is desirable for any reason as, for example, when it is desired to adjust or manually operate the lever arms 155 of the strapping devices or when making repairs.

The fluid pressure operated motors 102 which actuate the strap feeding devices 69 are connected to the supply pipe 280 through identical systems each comprising one of the air lines 310, 311 and 312 leading from the pipe 280 to one of the solenoid operated valves 313, 314 or 315. Each valve has two solenoids 313a and 313b, 314a and 314b, and 315a and 315b. An air line 316 leads from the valve 313 to one side of one air motor 102 and an air line 317 leads from the other side of this air motor back to the solenoid valve 313 which is provided with an exhaust line 318 leading to the atmosphere. Similarly, an air line 319 leads from the valve 314 to another motor 102 and an air line 320 extends from that motor back to the solenoid valve 314 which has an outlet 321. An air line 322 extends from the valve 315 to the other motor 102 from which an air line 323 leads back to the valve 315 which has an outlet 324. When the solenoid 313a is energized, air under pressure flows from the air line 280 through the valve 313 and through the air line 316 to the connected air motor 102, while at the same time air is exhausted from this air motor through the air line 317, the valve 313, and the exhaust line 318. Thus causes the motor 102 to be rotated in a direction whereby the strap is fed by the feed wheels 95 and 100 and extended around the bale or bundle 46. When it is desired to draw the strap taut around the bundle, the solenoid 313a is deenergized and the solenoid 313b is energized so that air under pressure is then fed through the air line 310 and the line 317 to the motor 102 which then rotates

in the reverse direction while at the same time air is exhausted by way of the air lines 316 and 318. When both of the solenoids 313a and 313b are deenergized the plunger of the solenoid valve 313 remains in a neutral position wherein both of the air lines 316 and 317 are connected to the air outlet 318, so that the motor 102 remains stationary. The other motors 102 are operated in a similar manner through the solenoid valves 314 and 315.

- 10 The cylinder 242 for effecting the elevation of the gripping dog 136 from its gripping position and the cylinder 275 by which the ejecting bar 250 is actuated to eject the strap from the sealing device are supplied with compressed air from the supply line 280 through an air line 325 which extends to a solenoid valve 326 having a solenoid 326a at one end and a spring return device 326b at its other end. From the solenoid valve 326 an air line 327 leads to one end of the cylinder 275. An air line 328 leads from the other end of this cylinder back to the solenoid valve 326 and an air line 329 connected to this valve exhausts to the atmosphere. A branch line 330 is connected to the line 328 and leads to one end of the cylinder 242 so that compressed air admitted through this line actuates the piston 243 and thereby operates the piston rod 241 to effect the elevation of the gripping dog 136 from its gripping position. A coil spring 331 mounted in the cylinder 242 is adapted to return the piston 243 to its initial position when the air pressure in the line 330 is relieved. Normally, the solenoid 326a is actuated by the spring return device 326b to cause air to flow through the lines 325 and 327 to the cylinder 275 and thereby actuates the piston 273 to cause the retraction of the piston rod 272. At the same time, air is exhausted from the rear end of the cylinder 275 through the air line 328, the solenoid valve 326, and the pipe 329 to the atmosphere. At the same time, the piston 243 in the cylinder 242 is retracted by the action of the spring 331 so that the gripping dog 136 then remains in its gripping position under the influence of its own spring. At the same time when the strap is to be ejected from the strapping device 75, the solenoid 326a is energized so that it counteracts the force of the spring return 326b to cause the plunger in the valve 326 to assume a position whereby air under pressure from the line 280 passes through the line 325 and then through the line 328 to the rear end of the cylinder 275 so that the piston 273 is then actuated to operate the ejecting bar 250 and the straps are thereby ejected from the sealing devices. Before this ejecting operation takes place, the air under pressure passing through the pipe 328 enters the cylinder 242 through the pipe 330 and actuates the piston 243 to cause the piston rod 241 to effect the elevation of the gripping dog 136 from its gripping position so that the straps may move freely from their positions beneath the gripping dogs 136 when the ejecting bars are operated. As the pistons 273 and 243 are extended, air is exhausted from the cylinder 275 through the line 327 and the exhaust line 329. The resistive force of the spring 331 in the cylinder 242 is intentionally made less than the force required to move the ejector bars 250 so that the piston rods 241 are always extended to release the gripping dog 136 before the ejector bars 250 are actuated.
- 65 In Fig. 31 there is illustrated diagrammatically the electrical system by which the solenoid operated valves shown in Fig. 30 are actuated and controlled. This system does not effect an automatic sequential performance of the several functions of the machine but it does provide means whereby the various operations may be effected selectively by the operator through the actuation of push buttons located in the control box 77 which is located conveniently at the front of the machine as shown in Fig. 2. This box 77 contains all of the switches which are manually actuated by the operator. The electric

circuit shown in Fig. 31 comprises two supply lines 340 which lead from a source of supply and are connected through the master switch 341 to the line conductors 342 and 343 between which various branch circuits are connected in parallel. These branch circuits and the parts connected therein will be described in connection with a description of the operation of the machine with the application of a single strap to a bundle.

Assuming that the straps 65 are to be passed around a bundle as described above and hereinafter, the first step is to raise the platen 45 which action is initiated by closing the "raise" button in the control box 77 to close the switch 344 which energizes the solenoid 285a of the valve 285 to cause air to flow in the proper direction into the air cylinders 62 to raise the pressure platen. When the platen has been elevated sufficiently, the switch 344 is released, thereby deenergizing the solenoid 285a so that the platen stops in a position which permits a bundle or bale 46 to be placed in a position beneath it after removing the previously bound bundle.

When the platen 45 starts to rise, the solenoid 326a of the solenoid valve 326 is also energized through the contacts 345a of the relay switch 345 which is then energized as the result of the preceding operating cycle. The energization of the relay switch 345 also closes its normally open contacts 345b which hold the relay 345 energized until the strap feed button is pushed to open the feed switch 347. With the solenoid 326a energized, the plunger in the solenoid valve 326 is positioned so that air under pressure causes the actuation of the dog releasing piston rod 241 and the strap ejector piston rod 272 to extend and cause the ejection of a previously joined strap from the base flanges 135a and 135b of the sealing device 75 by which that strap was applied to the bundle. Thus, the joined straps are ejected as the pressure platen starts to rise so that the bound bundle may be removed in readiness for placing a new bundle in position when the upward movement of the platen is arrested.

After the new bundle is in position, the next operation is to cause the straps 65 to encircle the bundle. This is accomplished through the operation of three switches 348, 349 and 350 which are mechanically connected to the switch 347 so that all four switches are operated simultaneously. When the feed switch 347 is opened by depressing the feed switch button in the box 77, the switches 348, 349 and 350 are simultaneously closed. The opening of the switch 347 deenergizes the relay 345, thereby opening the relay contacts 345a and 345b. The opening of the contacts 345b prevents the relay 345 from being again energized until three switches 351, 352 and 353 are again closed by the forward movements of the sealer arms 155 as hereinafter described. The closing of the switches 348, 349 and 350 causes the solenoids of three relays 355, 356 and 357 to be energized as current passes between the line conductors 342 and 343. The relay 355 is in series with the switch 348, a switch 358 and the previously described switch 80 which is actuated by the end of a strap 65 at the end of the feeding movement. Similarly, the relay 356 is in series with the switch 349, a switch 359 and a switch 80a which is actuated like the switch 80 by the end of another strap. The relay 357 is in series with the switch 350, a switch 360 and another strap actuated switch 80b.

As the relays 355, 356 and 357 are energized they each cause two sets of contacts to be closed. The relay 355 closes the holding contacts 355a and the contacts 355b, while the relay 356 closes the holding contacts 356a and the contacts 356b to be closed, and the relay 357 closes the holding contacts 357a and the contacts 357b. The closing of the contacts 355a, 356a and 357a prevents the solenoids of the relays from becoming deenergized upon release of the feed button which operates the switches 347, 348, 349 and 350. The closing of the contacts 355b, 356b and 357b energizes the solenoids 313b, 314b and 315b which cause the air motors 102 to be supplied with

compressed air through the valves 313, 314 and 315 so that they are rotated in the proper direction to effect feeding movements of the straps by the feeding devices 60. The feeding continues with the straps 65 being extended around the major portion of the bundle until their extremities strike the switches 80, 80a and 80b and open them. When these switches open the relays 355, 356 and 357 are deenergized but they are time delay relays so that the solenoids 313b, 314b and 315b are not opened until after an interval during which the feeding continues and the straps are projected upwardly through the switches 80a, 80b and 80c to form ends 65a of sufficient length to permit them to be projected manually over the bundle and into engagement with the gripping devices of the sealing units.

The solenoids 301a, 302a and 303a, by which the valves 301, 302 and 303, respectively, are actuated, are connected in branch circuits which are in parallel with the circuits of the time delay relays 355, 356 and 357, respectively. When these valves are operated they block the air lines 298, 299 and 300 to prevent the flow of air to the rear ends of the cylinders 167 by which the sealing levers 155 are actuated. The solenoid valves 301, 302 and 303 are controlled individually by the actuation of the two-way switches 358, 359 and 360, respectively, and are used only when it is desired to seal only one or two straps on a bundle instead of the maximum of three. When one of the solenoids 301a, 302a or 303a is actuated by moving the switch 358, 359 or 360 to close its circuit, the circuit of the associated relay 355, 356 or 357 is opened so that the associated set of relay contacts 355b, 356b or 357b can not be closed to cause the operation of the associated feed motor 102.

The switches 358, 359 and 360 are actuated by three buttons located in the box 77 and each button operates simultaneously one of the pairs of switches 358 and 361, 359 and 362, and 360 and 363. The switches 361, 362 and 363 are connected in parallel, respectively, with the switches 351, 352 and 353 which are actuated by the sealing levers 155 when these levers reach the limits of their sealing strokes. These same three buttons also actuate three other switches 364, 365 and 366 which are connected in parallel circuits for controlling the reverse operation of the motors 102 for tensioning the straps after their free ends have been gripped by the dogs of the sealing devices 75. The three buttons which actuate these various switches may be operated selectively to suit the number of straps which are to be fed, tensioned and sealed.

The closing of the switches 361, 362 and 363 permits the relay 345 to be energized independently of the switches 351, 352 and 353 which are actuated by the sealing levers 155, so that even though one or two sealing levers are not operated, thus permitting all operations to be performed with respect to the strap or straps which are selected for passing around the bundle, as hereinafter described. When it is desired to eliminate one or two straps, the switches 364, 365 and 366 prevent the actuation of the relays 367, 368 and 369, respectively, which control the tensioning operations of the strap feeding motors 104.

After the straps have been fed around the bundle and their ends positioned beneath the gripping dogs 136, the next step is to lower the pressure platen 45 which is brought about by pressing the proper button in the control box 77 to close the switch and thereby energize the solenoid 285b of the valve 285 to cause air to flow into the upper ends of the cylinders 62 and move the pistons therein and the pressure platen downwardly. The closing of the switch 370 also energizes a relay 371 which has contacts 371a connected in parallel with the switch 370 so that the solenoid 285b remains energized after the switch is released and the pressure platen compresses the bundle and holds it compressed during the subsequent portions of the strapping operation.

If it is desired to exercise manual control of the platen

45 while it is being lowered, a normally closed switch 372 in series with the relay 371 may be opened to prevent operation of the holding contacts 371a while permitting the operator to control the lowering of the platen by intermittent operation of the switch 370.

The relay 371 and the switch 372 are in series with a push button switch 373 which is operated simultaneously with the "raise" switch 344, being opened when the switch 344 is closed. The opening of the switch 373 deenergizes the relay 371 so that the holding contacts 371a are opened with the resulting deenergization of the solenoid 285b at the time when the solenoid 285a is energized by the closing of the switch 344.

When the platen has been lowered and the bundle compressed, the straps which have been extended around the bundle are tensioned through operations which are initiated by closing the push button switch 375 and thereby energizing the previously mentioned relays 367, 368 and 369 which are connected in series with the switches 364, 365 and 366, respectively. When the relays 367, 368 and 369 are energized their contacts 367a and 367b, 368a and 368b, and 369a and 369b, respectively, are closed. The contacts 367a, 368a and 369a maintain the circuit after the switch 375 is released. The closing of the contacts 367b, 368b and 369b causes the energization of the solenoids 313a, 314a and 315a by which the operation of the valves 313, 314 and 315 is controlled for effecting reverse operations of the motors 102 and the actuation of the feeding devices 60 to tension the straps. When the air motors have tensioned the straps to the point where the tension in the straps is equal to the force exerted on the straps by the air motors, as determined by the air pressure in the lines, the air motors stall and the platen 45 remains stationary during the subsequent strapping operations.

After the straps are tensioned around the bundle, the straps are cut off and their overlapping ends are sealed. These operations are effected by the admission of compressed air to the cylinders 167 through which the sealing levers 155 are actuated. When the lever arms 155 are in their retracted positions, as shown in Fig. 13, the adjustable pins 377 fixed therein engage the operating plungers of three switches 378, 379 and 380 to hold them in their closed positions, wherein the relays 367, 368 and 369 are energized and the air motors 102 maintain tension in the straps. As the sealing levers 155 start their forward pivotal movements the three switches 378, 379 and 380 are opened so that the relays 367, 368 and 369 are deenergized so that the air is cut off from the motors 102 and the tension in the straps due to the motors is relieved. However, the free ends of the straps are then held by the gripping dogs 136 and the supply portions are held by the dogs 140 so that the tension is maintained in those portions of the straps which extend around the bundle.

As the sealing levers 155 continue forwardly, the shearing blades 153 and 154 shear the supply portion of the strap. This is followed by the action of the sealing levers in actuating the jaws to form joints uniting the overlapping strap ends. This forward movement of the sealing levers 155 is initiated by closing the push button switch 381 which energizes the solenoid 296a of the valve 296, thereby causing the cylinders 167 to actuate the sealing levers in a forward direction. In addition, a normally closed contact 345c of the relay 345 completes the circuit of a relay 383 which is thereby energized to close its holding contacts 383a so that the circuit of the solenoid 239 is maintained after the switch 381 is released.

When the sealer arms 155 reach the forward ends of their strokes they engage and close the switches 351, 352 and 353, previously referred to. This action completes the circuit of the relay 345 which is thus energized to cause the contacts 345c to open and to close the contacts 345a and 345b. With the switch 345c opened,

the relay 383 is deenergized so that the contacts 383a open and the solenoid 296a is deenergized. The connections of the valve 296 are then changed due to the action of its spring return 296b so that air then enters the cylinders 167 to retract the sealing levers 155 to their normal positions shown in Fig. 13. The closing of the contacts 345b at this time is merely for the purpose of setting up a circuit for the next cycle. As the sealing levers 155 leave their forward positions, the switches 351, 352 and 353 are automatically opened, thereby deenergizing the relay 345 and causing the contacts 331 to return to their normally closed positions. With the return of the sealing levers 155 to their retracted positions the machine is ready for a new cycle of operations as above described.

In the foregoing specification and in the appended claims, unless otherwise specifically indicated, the term "bundle" is to be interpreted as including boxes, packages, containers, bales, filled bags or other objects which may be closed or compressed in the process of or preliminary to being strapped. For example, the "bundle" may be an overfilled box or container having a movable or telescoping cover which is closed by pressure, with or without compressing its contents, preliminary to applying the binding straps while maintaining the closed or compressed condition. The act of compressing the bundle, therefore, which is referred to in the claims, may consist in pressing a filled container sufficiently to close its cover or to an actual compacting of the bundle with consequent reduction in its size.

Thus, an important use of the invention is in strapping cartons or containers which are filled with textile materials or the like, whereby the power actuated pressure platen serves to move to closed position the parts which form the cover of the container and to compress the contents sufficiently for that purpose, and then to maintain the container and its contents under that degree of compression while a plurality of binding straps are successively applied around the container and their ends joined while they are under tension so that the bound object is retained by the straps in the condition to which it has been compressed.

Although one form of the improved bale strapping machine has been shown and described by way of illustration, it will be understood that it may be constructed in various other forms without departing from the scope of the appended claims.

We claim:

1. The combination in a strapping machine, of a frame having a base for supporting a bundle and an upwardly extending standard, a pressure platen mounted at its rear edge on said standard for vertical movement thereon, means for moving said pressure platen toward and from said base, feeding means mounted on the forward portion of said pressure platen for withdrawing a strap of magnetizable material from a supply and extending it endwise around a bundle on said base, and a series of magnetic rollers mounted on said standard and on the underside of said pressure platen for holding said strap away from said bundle and guiding it during its movement around said bundle.

2. The combination in a strapping machine, of a frame having a base for supporting a bundle and an upwardly extending standard, a pressure platen mounted at its rear edge on said standard for vertical movement thereon, means for moving said pressure platen toward and from said base, feeding means mounted on the forward portion of said pressure platen for withdrawing a strap of magnetizable material from a supply and extending it endwise around a bundle on said base, and a series of magnetic rollers mounted on said standard and on the underside of said pressure platen for holding said strap away from said bundle and guiding it during its movement around said bundle, said magnetic rollers being dis-

tributed on said standard to attract the upright portion of said strap in all positions of said pressure platen.

3. The combination in a strapping machine, of means for supporting a bundle, means for withdrawing a strap of magnetizable material from a supply and extending it substantially around said bundle, means including magnetic rollers for supporting and guiding said strap while it is being so extended, and nonmagnetic stationary members associated with said rollers for preventing the strap from bending around said rollers while in contact therewith.

4. The combination in a strapping machine, of a base for supporting a bundle, a platen, pressure means for moving said platen toward said base to compress said bundle, said platen having a first guide channel for the passage of a strap for binding said bundle, a second guide channel extending in the direction of movement of said platen from adjacent said base to a position opposite said first guide channel in all positions of said platen, the end of said first guide channel being positioned to direct the free end of a strap into said second guide channel at all positions of movement of said platen to accommodate automatically a wide variety of sizes of bundles, and a third guide channel positioned to receive the strap from said second guide channel and to direct the strap across said base, whereby the strap is guided around the bundle while the bundle is held compressed.

5. The combination in a strapping machine, of a base for supporting a bundle, a platen, pressure means for moving said platen toward said base to compress said bundle, said platen having a first guide channel for the passage of a strap of magnetizable material for binding said bundle, a second guide channel extending in the direction of movement of said platen from adjacent said base to a position opposite said first guide channel in all positions of the platen, the end of said first guide channel being positioned to direct the free end of a strap into said second guide channel at all positions of movement of said platen to accommodate automatically a wide variety of sizes of bundles, magnetic rollers mounted on said second guide channel along the entire length thereof to provide a roller adjacent the associated end of said first guide member in any position of said platen to hold the strap away from the periphery of the bundle, and a third guide channel positioned to receive the strap from said second guide channel and to direct the strap across said base, whereby the strap is guided around the bundle while the bundle is held compressed.

6. The combination in a strapping machine, of a frame having an upwardly extending standard and a base for supporting a bundle, a pressure platen mounted at its rear edge on said standard for vertical movement thereon, means for moving said pressure platen toward and from said base to accommodate a wide range of sizes of bundles therebetween, feeding means mounted on the forward portion of said pressure platen for withdrawing a strap from a source of supply and extending it endwise

around a bundle on said base, means for guiding said strap rearwardly from said feeding means over the top of said bundle, thence downwardly on the rear side of said bundle and thence upwardly on the front side of said bundle, a housing mounted forwardly of and above said base to receive the strap as it passes upwardly on the front side of the bundle, and control mechanism mounted in said housing in position to be contacted by the free end of the strap and operative when contacted thereby to stop said feeding means to position the free end of the strap a predetermined distance above said housing for any adjusted position of said platen, whereby to provide the proper length of strap for any of a wide range of sizes of bundles.

7. The combination in a strapping machine, of a frame having an upwardly extending standard and a base for supporting a bundle, a pressure platen mounted at its rear edge on said standard for vertical movement thereon, means for moving said pressure platen toward and from said base to accommodate a wide range of sizes of bundles therebetween, feeding means mounted on the forward portion of said pressure platen for withdrawing a strap of magnetizable material from a source of supply and extending it endwise around a bundle on said base, means for guiding said strap rearwardly from said feeding means over the top of said bundle, thence downwardly on the rear side of said bundle and thence upwardly on the front side of said bundle, a housing mounted forwardly of and above said base to receive the strap as it passes upwardly on the front side of the bundle, control mechanism mounted in said housing in position to be contacted by the free end of the strap and operative when contacted thereby to stop said feeding means to position the free end of the strap a predetermined distance above said housing for any adjusted position of said platen, whereby to provide the proper length of strap for any of a wide range of sizes of bundles, and magnetic rollers mounted on the under side of said platen and on the forward side of said standard to hold the strap in a predetermined path around the bundle and spaced outwardly from the periphery thereof for any of a wide range of sizes of bundles and in any adjusted position of said platen.
